UNITED STATES PATENT OFFICE.

JAMES POWERS, OF NEW YORK, N. Y., ASSIGNOR TO POWERS ACCOUNTING MACHINE COMPANY, OF NEW YORK, N. Y., A CORPORATION OF DELAWARE.

METHOD OF FEEDING CARDS.

1,310,434.

Specification of Letters Patent. Patented July 22, 1919.

Original application filed March 18, 1916, Serial No. 85,130. Divided and this application filed June 13, 1918. Serial No. 239,861.

To all whom it may concern:

Be it known that I, JAMES POWERS, a citizen of the United States, residing in New York city, in the county of New York and State of New York, have invented certain new and useful Improvements in Methods of Feeding Cards, of which the following is a specification.

This invention relates to card feeds in general, and more particularly to a method for feeding perforated cards to accounting machines and the apparatus for carrying out such method.

The invention herein described and claimed relates to subject matter divided from and described and previously claimed in my copending application, Serial No. 85,130 filed March 18th, 1916, for card feed for statistical card accounting machinery.

The present invention contemplates the method of feeding cards through a machine whereby the cards may be carried into the machine in a vertical position and again discharged in a vertical position, such vertical positioning of the cards greatly facilitating the manipulation of the cards both when supplying the machine with cards and removing the cards therefrom after having been discharged, the cards being discharged in the same consecutive order as conveyed into the machine.

It is further contemplated to provide a method and apparatus for carrying out such method whereby the cards may be received in a vertical position, deflected into a horizontal position to be analyzed, and then deflected back to vertical position and discharged from the analyzing mechanism.

These and other features, capabilities and advantages of the present improvement will appear from the subjoined detail description of one specific embodiment thereof, illustrated in the accompanying drawings, in which—

Figure 1 is a side elevation of a printer tabulator equipped within the present improvement.

Fig. 2 is a fragmental side elevational view of the printer tabulator showing the initial card feeding means partly in section.

Fig. 3 is a plan view of the mechanism shown in Fig. 2.

Fig. 4 is a fragmental end elevation, partly

in section, showing the initial card feeding means.

Fig. 5 is a fragmental side elevation showing the card discharging means with a card-packing means in card-receiving position.

Fig. 6 is a front elevation with the printer tabulator removed, showing the discharging means.

Fig. 7 is a fragmental view, partly in section, along the line 7—7 of Fig. 5.

Fig. 8 is a fragmental view showing the card-packing means of the discharging means in packing position.

In the embodiment shown, the apparatus comprises essentially a main frame A for an accounting machine, of the printer tabulator type such as illustrated in my copending application Serial No. 85130, filed March 18th, 1916, to the rear end of which is formed an auxiliary frame B having a bracket 11 on which are formed two parallel bed rails 12, on which the edges of the cards C rest, being vertically supported thereon and extending across the same, and on which the lower edge of the follower 13 also rests, the front face of which follower is preferably provided with a pad 14, or the like, for contacting with the cards C. The rear face of said follower 13 is provided with the bearings 15 through which the shaft 16 extends, the ends of which shaft 16 are secured in the forward extensions of the lateral portions 17 of the transverse plate member 18, the lateral portions 17 being connected to one another by the transverse bar 19. The lateral portions 17 are provided with grooves 20 for engaging the guide-rails 21 secured to and disposed above the bed rails 12.

By the foregoing arrangement, it is thus seen that the follower 13 is pivotally connected to the plate member 18. Medially of the bar 19 there are formed two rearward bearings 22 for the shaft 23 which extends through the vertically extending slot 24 formed in the walking pin 25, the upper portion of which is resiliently connected to the collar 26 formed on the shaft 16 by the coil spring 27, and the lower end of which is connected by the flat loop-spring 28 with the transverse bar 19 by means of which the upper portion of the pin 25 will be resiliently strained against the rearwardly extending plate portion 29 formed on the transverse

bar 19. The plate portion 29 is adapted to engage the notch 30 formed in the pin 25 when the pin is raised into idle position with the lower end of its slot 24 engaged by the 5 shaft 23. The lower end of the pin 25 is formed into a rack-engaging finger 31 with an inclined face 32 on its forward side, such finger being adapted to engage the rack 33 when the pin 25 is released in its depressed 10 or active position, the rack 33 being slidably supported on and guided in the brackets 34 and 35, the bracket 34 being secured to the cross-piece 36 fixed to the rear ends of the bed rails 12, and the bracket 35 secured to 15 the main frame A. The rack 33 is provided with teeth 37, the rear faces of which are inclined, while their front faces are substantially vertical, the arrangement being such that the finger 31 may ride over the teeth 20 37 on the rearward reciprocation of the rack 33 but be engaged and rocked on the forward reciprocation of the rack 33.

For reciprocating the rack 33, the finger 38 is provided, which is fixed to the shaft 39 25 mounted in the bearings 40 and secured to the bed rails 12, the lower edge of the rack 33 having a notch 41 formed therein to receive the finger 38. The shaft 39 has fixed thereto a forwardly extending arm 42 which 30 is pivotally connected to the vertically reciprocating link 43, the lower end of which is pivotally connected to the rearwardly extending arm 44 of the bell-crank 45 pivotally mounted on the shaft 46 and having a forwardly extending arm 47, to the front end 35 of which is secured a cam roller 48 for engagement with the cam-groove 49 of the cam 50 fixed to the main driving shaft 72.

The main frame A on either side of the 40 card-receiving end of the bed rails 12, is provided with upwardly extending side members 61 extending upward to the height of the cards C, on the upper edges of which are secured the guiding plates 52 which extend inwardly across the path of movement 45 of the cards C, the rear ends of which are flared upwardly to facilitate the passage of the cards thereunder.

Vertically reciprocable between the guide- 50 plates 52, is provided the picker-bracket 53 on which is formed the card picker-plate 54, the bracket 53 being pivotally connected to the upper end of the link 43. The ends of the bracket 53 are guided between the fingers 55 and 56 formed on the side members 61, the rear faces of the fingers 55 being inclined so that their lower edges extend a little rearwardly of the picker-plate 54, while their upper edges are in alignment 55 with the picker-plate 54. There is provided an adjustable block 57, the front face of which is inclined to cooperate with the rear faces of the fingers 55, to the lower end of which block 57 is secured the curved deflect- 60 ing plate 58 with which the rollers 59 and

60 coöperate to deflect the cards C, as they are lowered by the picker-plate 54, to the feed roller 61 by which such cards C are fed into analyzing position for setting the printer tabulator.

After the cards C have been analyzed, they are conveyed by the roller 61 to the rollers 62 and 63, the upper roller 62 being disposed forwardly of the roller 63 and with the lower levels of their peripheries extending down below the upper levels of the peripheries of the rollers 63 so that the cards C may be deflected downwardly by such rollers 62 and 63 on to the rockable deflecting plate 64, such plate 64 also serving as a card-packing member.

The deflecting plate 64 is secured to the shaft 65 and journaled in the rear end of the bed rails 66 of the bracket 67 extending forwardly of and secured to the main frame A, 85 such plate 64, when disposed in its rearward position, being inclined to receive the cards C from the rollers 62 and 63, and when disposed in its forward position being substantially vertical, thereby carrying the cards C 90 over onto the bed rails 66. For rocking the plate 64, a short lever 68 is secured to and extends downwardly from the shaft 65, the lower end of which lever 68 is pivotally connected to the lever 69 provided with the cam link 70 at its rear end which encircles the cam-disk 71 fixed to the main driving shaft 72. Formed on the bracket 67 and extending above the bed rails 66 to either side of the path of movement of the cards C, are 100 formed the bearings 73 and 74, the bearings 73 being secured adjacent to the main frame A, and the bearings 74 at the extreme front end of the bracket 67. The bearings 73 and 74 mount the shafts 75 which extend through 105 the collars 76 formed on the lateral ends of the plate 77. The plate 77 will be gradually carried forward by the increasing supply of cards being packed thereagainst by the plate 64.

For anchoring the cards C in place on said bed rails 66 and preventing the same from returning with the plate 64, the U-shaped rod or wire 78 is provided, the ends of which are pivotally connected to the upwardly extending plate portions 79 formed on the frame A and extending upward on either side of the path of movement of the cards C, being conveyed to the bed rails 66. The wire 78 has an intermediate connecting portion 80 resiliently maintained downward against the rear face of the last discharged card by the springs 81 connecting the end portions 82 of such wire 78 with the plate portions 79. This wire 78 cooperates with the plate 64 as follows:—As a card C is carried forward by the plate 64, the upper edge of the card being so carried will be pressed against the intermediate portion 80 thereby thrusting it upward out of the way to per-

70

mit the card to pass thereunder, the plate 64 moving forward the supply of cards C disposed on the bed rail 66 and at the same time the plate 77, the thickness of a card, and as soon as the upper edge of the card being so carried has slipped past the intermediate portion 80, the wire 78 will be free to snap against the rear face of such card, and the plate 64 will thereupon be permitted to return to inclined position without danger of returning such last discharged card with it.

For assisting in frictionally holding the plate 18 in advanced position, the friction angle plates 83 are provided which are pivotally connected to the rearward extensions 84 of the lateral portions 17, such plates 83 having knife-edges 85 for engaging the guide-rails 81, and springs 86 for resiliently maintaining such knife-edges 85 in engagement with such rails 21, the knife-edges 85 being disposed at an angle to such rails 21, so that the free movement of the lateral portions 17 in a forward direction will be permitted, while the knife-edges 85 will be adapted to engage into the rails 21 and frictionally hold the lateral portions 17 and therewith the bar 18 from freely moving rearward.

The operation of the initial feeding means is substantially as follows:—Every time the picker-plate 54 descends to lower a card C, the rack 33 rocked forwardly by the finger 38, and the finger 31 thereby engaged by one of the teeth 37, the lower end of the pin 25 will be drawn upwardly against the pressure of the springs 27 and 28, which strain of the springs 27 and 28 will exercise a pushing strain on the bar 18 and due to a card C having been discharged, the supply of cards C on the bed rails 12 and the follower 13 will thereby be permitted to move forward the distance of a thickness of a card, the friction-plates 83 permitting free movement of the bar 18 in a forward direction and frictionally taking a fresh bite on the rails 21 when the bar 18 comes to rest, thereby to prevent the return of the bar 18 with the thereupon ensuing rearward reciprocation of

the rack 33. The pin 25 will rise slightly with the rearward movement of the rack 33, but due to its springs 27 and 28 will again drop into firm engagement with a tooth 37 as soon as the rearward movement ceases. This operation of the pin 25 will be repeated until all the cards have been fed into the machine, whereupon the follower 13, being then maintained against further forward movement, the pin 25 will be merely repeatedly rocked against the strains of the springs 27 and 28. When it is desired to move the bar 18 and follower 13 rearward for a fresh supply of cards C, or for any other reason, it is only necessary to raise the pin 25 out of coöperation with the rack 33, in which operation the pin 25 is raised until its notch 30 engages the plate 29 whereby the pin 25 will be anchored out of engagement with the rack 33 and permit the free movement of the bar 18 rearward, the friction plates 83 being at this time merely pressed rearward to disengage them from the rails 21.

It is obvious that various changes and modifications may be made to the details of construction and to the steps of the method without departing from the general spirit or scope of the invention.

I claim:

A method of analyzing cards, said method consisting in vertically positioning the cards in an initial pack right side up with their faces forward; feeding the cards, one at a time, face forward; deflecting the fed cards to horizontal position; analyzing the deflected cards; again deflecting the analyzed cards again to vertical position with their faces forward; and discharging the again deflected card into a final pack right side up with their faces forward and in vertical position, the cards having the same relative position and arrangement in the initial and final packs.

JAMES POWERS.
